UNITED STATES PATENT OFFICE

114,871

DESIGN FOR A BOOK END

Rudolph Dopyera, Los Angeles, Calif.

Application July 12, 1938, Serial No. 78,419

Term of patent 7 years

To all whom it may concern:

Be it known that I, Rudolph Dopyera, a citizen of the Republic of Czechoslovakia, residing at Los Angeles, in the county of Los Angeles and State of California, have invented a new, original, and ornamental Design for a Book End, of which the following is a specification, reference being had to the accompanying drawing, forming a part thereof.

In the drawing, Fig. 1 is a front elevational view of the book end, showing my new design;

Fig. 2 is a side elevational view of the book end; and

Fig. 3 is a top plan view of the book end.

I claim:

The ornamental design for a book end, as shown.

RUDOLPH DOPYERA.
